RIVET HEADING MACHINE.

No. 578,359.

Patented Mar. 9, 1897.

UNITED STATES PATENT OFFICE.

FERDINAND PHILIPS, OF PHILADELPHIA, PENNSYLVANIA.

RIVET-HEADING MACHINE.

SPECIFICATION forming part of Letters Patent No. 578,359, dated March 9, 1897.

Application filed April 29, 1896. Serial No. 589,549. (No model.)

To all whom it may concern:

Be it known that I, FERDINAND PHILIPS, a subject of the German Emperor, residing in the city and county of Philadelphia, in the State of Pennsylvania, have invented a new and useful Improvement in Rivet-Heading Machines, of which the following is a true and exact description, reference being had to the accompanying drawings, which form a part of the specification.

My invention relates to rivet-heading machines, and has for its object to improve the construction of such machines, particularly with reference to the operation and adjustment of the knock-out pin or rod and to the adjustment of the die in which the blanks are placed.

The nature of my improvements will be best understood as explained with reference to the drawings, in which they are illustrated, and in which—

Figure 1 is a front elevation of the rivet-heading machine; Fig. 2, a side elevation thereof, taken on the section-line 1 1 of Fig. 25 1. Fig. 3 is a cross-sectional view on the section-line 2 2 of Fig. 2, and Fig. 4 is a cross-section on the line 3 3 of Fig. 2.

A is the frame of the machine, A' being a bracket attached thereto for supporting the 30 shaft B; A², the portion of the frame upon which the lower die is supported, a² being an opening in said portion of said frame adapted to come beneath the die. A³ A³ are projections of the frame having their opposed faces 35 a³ outwardly inclined, as shown in Fig. 3.

B is the driving-shaft, to which is attached the driving-pulley B' and a pinion B², which engages a spur-wheel C, the hub C' of which is, as shown, clamped between flanged rings 40 C² C² by means of bolts C³, the rings C² being secured so as to turn with the shaft D.

D' is a crank in shaft D, to which is connected the connecting-rod E, having, preferably, trunnion-like pins E' forged at its head, 45 said pins being secured to the box F F' and to the reciprocating head G by bolts F². The head G is guided by guides H H upon the frame and is formed with an opening G' in its face, upon the bottom G² of which rests the 50 block G⁴, having a threaded perforation G⁵.

G³ is a perforation through the lower part

of head G, formed in line with the perforation in block G⁴.

G⁶ is a binding-screw in block G⁴, and G⁷ a similar screw for die J in the base of head G. 55

I is an adjusting-screw working in block G, the lower end of which abuts against the heading-die J, J' being the operative head of said die.

K is a plate lying between the frame and 60 head G.

L is a plate secured above and in front of the portion A² of the frame by bolts l l.

M is a block resting on A² and against the plate L. It is provided with a perforation 65 M', in which is placed a sleeve N, the head N' of which rests on base A² or a part supported thereby. The sides m m of the block M are formed in converging planes, the angle of convergence being preferably the same 70 as the angle of divergence of the walls a³ a³, between which the block M lies.

U U are wedges formed to fit against the oppositely-lying faces m and a³ and provided with bolt extensions U', extending through 75 openings in the plate L and by which the wedges can be drawn up by means of nuts on the outside of the plate. It is obvious, of course, that by a manipulation of the wedges U U the block M can be shifted from side to 80 side and rigidly securely held in any desired position.

O is the lower or rivet-holding die of the machine. It is formed with a longitudinal perforation O', in the top of which the rivet-blank is placed, and the die, as shown, fits into the sleeve N and rests upon the plate N' 85 below the sleeve.

P is a sleeve fitting and resting in the perforations a² of the frame-plate A² and provided with an exterior thread, as indicated at P', upon which thread screws the adjusting-nut Q, having a perforation Q' through its center, and slots, as Q², extending through its 90 sides to its central cavity.

W is the knock-out pin or rod, the upper end of which extends through the perforation of the headed sleeve N and lies in the perforation O' of the die o. The height to which this pin normally extends in the die O 100 is determined by the length of the rivet-blank to be headed, as in normal position it serves

as a stop or a rest upon which the lower end of the rivet-blank rests. Its other function is to serve as a knock-out pin to force the rivet out of the die after it has been headed, 5 and it is a prime object of my invention to provide mechanism which, irrespective of the adjustment by which a varying normal position is given to the pin, will always raise it to the same height when it performs its function 10 as a knock-out pin.

It is found convenient to make the pin W only of sufficient length to perform its necessary functions and to provide it with what is in effect an extension, (represented by the rod 15 marked R in the drawings.) The upper end of this rod extends into the sleeve P and is provided with a shoulder R', which rests upon the head of the nut Q, while an extension R² of the rod extends through the nut.

20 It will readily be seen that by the construction shown the rod R and the pin W, which it supports, can be adjusted to any desired normal height by simply turning the nut Q, and I will here state that my reason for forming the slots Q² in the nut is to permit the free escape of the water which is kept intermittently running through the die O, from which it passes to the sleeve P and thence to the nut Q, from which it escapes through the 25 slots Q². I find this an advantageous construction, because it enables me to keep the water practically out of contact with the threaded nut P' of the sleeve P, thus avoiding the rusting of this portion, which would 30 interfere with the rod adjustment of the nut.

35 S is a cross-bar supported by rods T T, which rods in turn are secured to the rods G⁸ G⁸, extending out from the lower end of the head G. The function of this cross-bar is to come in 40 contact at proper intervals with the lower end R² of the rod R, pushing it and the pin W upward to thrust the rivet out of die O, and it will be seen that by the construction illustrated the knock-out pin will always be thrust 45 upward to the same height, irrespective as to whether in normal adjustment it is raised or lowered. To obtain a nice adjustment, it is, however, desirable that the point to which the pin shall be forced upward should be adjustable, and this I secure by forming a circular 50 threaded perforation S' in the cross-bar S, into which screws a screw S². Obviously by turning this screw it may be raised or lowered, and thus an adjustment made as to the height 55 to which the knock-out pin will be raised. In order to prevent breakage of the machin-

ery, I prefer to have neither the bar S nor the screw S² strike directly upon the rod R, but to construct them with a perforation, as S⁴, preferably of rectangular form and provided 60 on opposite sides with shoulders S³, upon which shoulders I rest a break-bar S⁵. In case of unusual pressure this break-bar on coming in contact with the rod R² will break in the middle and fall through the rectangular perforation S⁴, permitting also the end R² of the rod to pass through the perforation and thus avoiding breakage in the machine. 65

Having now described my invention, what I claim as new, and desire to secure by Letters 70 Patent, is—

1. In a rivet-heading machine the combination with a die as O having a perforation O' in which the rivet rests, of a rod as W longitudinally movable in perforation O', means 75 as nut Q adjustable to and from die O for supporting rod W, a reciprocating rod-raiser or cross-bar S moving through a determined path unaffected by the adjustment of nut Q and an adjustable stop as S² secured to bar S 80 and through which it acts upon the rod.

2. In a rivet-heading machine the combination with a die as O having a perforation O' in which the rivet rests, of an externally-threaded hollow sleeve P secured in line with 85 the die, an adjusting-nut Q adapted to screw on said sleeve P and having slots Q² formed in it to permit the escape of water, and a knock-out rod as R passing through and adapted to be supported by the nut as speci- 90 fied.

3. In a rivet-heading machine having a perforated die as O and a knock-out rod movable therein, the combination with a reciprocating bar as S adapted to act upon and raise the pin 95 at proper intervals and having an opening in its face, of a break-bar S⁵ supported over said opening at its ends only and by means of which the knock-out rod is raised.

4. In a rivet-heading machine having a per- 100 forated die as O and a knock-out rod movable therein, the combination with a reciprocating bar as S adapted to act upon and raise the pin at proper intervals, and having a circular threaded opening in its face, of a screw S² 105 having an opening S⁴ formed through it and a break-bar S⁵ supported at its ends only across said opening.

FERDINAND PHILIPS.
